(57) **CLAIM**

The ornamental design for a vehicle rearview mirror having a set of downward illuminating LEDs activated by a battery-operated switch, as shown and described.

DESCRIPTION

FIG. 1 is a front elevational view of a vehicle rearview mirror having a set of downward illuminating LEDs activated by a battery-operated switch. The light beam projecting downward from each of the LEDs is shown in broken lines for illustrative purposes only and forms no part of the claimed invention;

FIG. 2 is a rear elevational view thereof;

FIG. 3 is a top plan view thereof;

FIG. 4 is a bottom plan view thereof;

FIG. 5 is a rear side elevational view thereof; and,

FIG. 6 is a left side elevational view thereof.
